CLAIM

The ornamental design for a binder for large sheets, as shown and described.

DESCRIPTION

FIG. 1 is a top perspective view of a binder for large sheets in a fully opened position, with the three fastener strips unfastened, showing my new design;

FIG. 2 is a front elevational view thereof, in a fully closed position, with the three fastener strips fastened, the rear being a mirror image;

FIG. 3 is a left side elevational view thereof;

FIG. 4 is a right side elevational view thereof; and,

FIG. 5 is a top plan view thereof, the bottom view being a mirror image of the top view shown in FIG. 5.
